CLAIM

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a front view of a display screen or portion thereof with graphical user interface according to my design.

The dashed broken lines at the perimeter of the FIGURE illustrate the display screen or portion thereof, and the broken line showing of text illustrates portions of the graphical user interface. None of the broken lines form part of the claimed design.
